CLAIM

The ornamental design for a device for securing a guardrail to a pour stop, as shown and described.

DESCRIPTION

FIG. 1 is a front perspective view of a device for securing a guardrail to a pour stop showing my new design;

FIG. 2 is a front elevation view thereof;

FIG. 3 is a front elevation view of FIG. 2 disposed above a pour stop, the broken lines depict environment that forms no part of the claimed design;

FIG. 4 is a front elevation view of FIG. 2 disposed upon a pour stop, the broken lines depict environment that forms no part of the claimed design;

FIG. 5 is a right-side elevation view of FIG. 2;

FIG. 6 is a top plan view of FIG. 2; and,

FIG. 7 is a bottom plan view of FIG. 2.

1 Claim, 6 Drawing Sheets
